UNITED STATES PATENT OFFICE.

CHARLES H. WILD, OF BALTIMORE, MARYLAND, ASSIGNOR TO BURT MACHINE COMPANY, INCORPORATED, A CORPORATION OF MARYLAND.

CASE-FILLING MACHINE.

Application filed March 1, 1918. Serial No. 280,139.

To all whom it may concern:

Be it known that I, CHARLES H. WILD, a citizen of the United States of America, residing in the city of Baltimore, State of Maryland, have invented certain new and useful Improvements in Case-Filling Machines, of which the following is a specification.

This invention relates to a machine for filling cases or boxes with cans, cartons, bottles or the like, and is of the general type of this disclosed in United States Patents No. 1,152,997 of September 7, 1915, and No. 1,253,997 of January 15, 1918.

Broadly, it consists of a loading or filling plunger, means for retaining the cans in the path of the plunger in a group of number and form to fit the case, means for leading the cans to the retaining means, positioning and supporting means for the casing in line with the path of the plunger, and means for actuating the plunger to move the cans as grouped from the grouping means to and into the case or box.

The present machine, though it has the essentials of the machines of the prior patents, includes important additional features and improvements which contribute to a more uniform, continuous, satisfactory and efficient operation.

The principal objects are to produce a machine which is not subject to cramping of the receptacles or cans, which is capable of handling without injury or crushing all receptacles, containers, cartons or cans whether they be filled, i. e., closed at both ends or empty and open at one end or variously flanged as in the case of cans arranged for solderless closure and which without any backward thrust of the supply is capable of handling the cans, packages and receptacles labeled for shipment in all instances without injuring the most fragile package or scraping or otherwise damaging the labels, particularly by the loading stroke which removes the cans from the path of the supply.

Another important consideration is the production of a machine which is adjustable as to all dimensions which limit the size of the load both as to the length and diameter and the number of the cans or packages handled so that a single machine is capable of handling cans of different lengths and diameters and packing them in differ-

ent sized cases holding different numbers of cans.

More particularly, the present machine embodies novel features by virtue of which the cans, the term being used in a broad sense as applying to cans, bottles, paper boxes, bottles wrapped in paper, and all packages which would be shipped in cases or boxes and arranged for shipment as cans are packed and arranged for the same purpose, are grouped in the path of the plunger and separated from those on the track, ways or conveyor, leading to the retaining means by which they are held so grouped, without imparting to them any backward thrust which tends to cause cramping, interruption to the supply and crushing of the articles.

Another feature of the new machine is a device whereby scraping or rubbing of the articles to be packed upon each other to a point where the lots are divided is prevented. This end is effected in the present device by a motion imparted to the can stop, so that the group or load when cut off by the separator is permitted to move forward out of contact with the supply, the forward motion taking place just after the operation of the separator prior to the forward stroke of the plunger.

In the accompanying drawing I have illustrated a machine embodying the various features of my invention. In this drawing—

Figure 1 is a plan view of the machine.

Figure 2 is an elevation looking at the machine from the end toward which the cans are fed.

Figure 3 is a side elevation looking from the left in Figure 2, the receiving end being broken away.

Figure 4 is a side elevation of the end of the machine broken away in Figure 3 taken from the opposite side.

Figure 5 is an elevation of the escape- 100 ment lock controlling the can stop looking from the right in Figure 3.

Figure 6 is a front view of the same; and

Figure 7 is a plan of the separator gear- 105 ing.

Referring to the drawings by numerals, each of which has the same significance in the different figures, the frame of the machine as illustrated consists of a central member 1 known as a yoke, to the opposite 110

sides of which are secured parallel steel bars 2, 3 known as side bars, to which are secured various uprights carrying the tracks, shelves, etc., composing the grouping means 5 and the means for leading the articles to be packed to the grouping means.

More specifically, the side bars carry at the left in Figure 1 upright plates 4 and 5 known as the front and back side plates, 10 respectively, one secured to each bar and having their surfaces parallel to the length of the bars. These side plates have feet 6, 7 resting each on the corresponding side bar and secured by means of bolts or cap screws 15 8. The foot of one of these side plates, preferably the front side plate, is slotted as indicated at 9 to provide for lateral adjustment. These side plates are braced at the top by a transverse member 10 which may 20 be duplicated and made in several lengths to provide for the differences of adjustment, and these are further spaced by likewise variable studs 10' and 10".

The direction of feed of the cans or 25 articles being packed is from left to right as seen in Figures 1 and 3. Progressing now in the direction of the feed we come next to the front and rear shelf and track supports 11 and 12, respectively. These are uprights 30 each secured at its foot to the corresponding side bar and the front member 11 is made adjustable at right angles to the side bars as is the front side plate 4, the foot 13 being slotted for this purpose at 14. At the 35 extreme end of the machine in the direction of the feed I have an upright frame 16 having a solid base 17 which fits between the side bars and is rigidly secured as by bolts 18 engaging a transverse bar 19 which is 40 drawn by the bolts upward against the bottom sides of the side bars. This end member or frame 16 has uprights 20 at front and rear, and a transverse top connecting member 21.

45 The side plates 4 and 5 and the track supporting members 11 and 12 carry a series of horizontal tracks 25 shown as composed of angle irons. The adjustment of these tracks as to their width to accommodate 50 cans of different lengths is provided for by adjustment of the side plate 4 and the support 11, that is, the adjustment transversely of the side bars of the rear side plate and the rear support just described. The members 11 and 12 are secured together at the 55 top by a strut 12' made in different lengths and interchangeable. These tracks are also made adjustable in a vertical direction, i. e., the upper two tracks as shown are so adjustable 60 to provide for variation in the diameter of the cans or packages to be packed. This adjustment in the form of the invention shown is of the ordinary screw and slot type, the screws being indicated by 65 reference character 26 and slots by reference

character 27; but a means of determining this adjustment as to certain points is provided by swinging plates 28 pivoted at 29 and having arcuate slots 30 concentric with said pivots. This makes it possible to give 70 the tracks these different adjustments quickly and conveniently providing for different diameters and lengths of packages and cans.

In the statement of invention we have referred to means for retaining the cans in the path of the plunger and holding them grouped in an arrangement to fit the case or box in which they are to be packed. This means consists of the shelves 31, 32, 33, the 80 separators 38, 39, 40 and the can stops 35, 36, 37 to be described. The lower shelf is more properly the bed of the machine or bottom plate which is stationary. The upper and middle shelves 31 and 32 are adjustable to 85 provide for variation in the diameter of the cans or packages being packed. In the present instance the feed end of the upper shelf and the feed end of the middle shelf rest upon the adjacent ends of the corresponding tracks and are adjusted with them. The opposite ends, i. e., the ends adjacent the can stops, are supported on cross bars 42, 43 secured to the uprights 20 of the rear feed frame, and these are made 95 adjustable by providing a series of holes 44 for the bolts 45 by which they are secured.

90 Adjustment of the length of the group of cans, i. e., the length of each tier of cans is accomplished by moving the end frame 16 along the side bars 2, 3, the same being clamped by means of the bolts 18 already described seated in the cross bar 19. This end frame is positioned by means of a pin 49 to be inserted in any of a series of holes 50. 105

100 The loading operation is accomplished by the plunger or multiple plungers 46, 47, 48 which are made adjustable as to their length, this adjustment being accomplished in the present instance by moving the horizontal extension members or angles 51, which are secured to the plunger castings 52 and form the plunger surfaces, in the direction of their length. These angles are held in position by bolts 53 fitted to a series of holes 110 54 in the castings and angles. The adjustment of the plungers corresponds to the adjustment of the end frame and provides for the handling of varying numbers of cans in a tier or tiers of varying length due to packing cans of different diameters, and the adjustment of the can stop arms and separator arms vertically on their shafts, as herein-after described, corresponds to the vertical adjustment of the shelves and the tracks, 115 and provides for the handling of cans and packages of different diameters, and if desired may be arranged to provide for a different number of tiers.

120 It will also be noted in this connection 130

that the can stop arms 56 are adjustable vertically on their shaft 57, and the separator arms are vertically adjustable on their shaft 59.

5 The plungers, the can stops and the separators with their actuating means will be more specifically described.

The plunger group consists of what may be termed a plunger body 60 in the form of 10 an upright plate to which are secured three horizontally projecting plunger castings 52 each in the form of a frame projecting at right angles to said plate inward toward the centre of the machine and having an 15 elongated plunger member 46, 47, 48 extending transversely at its inner extremity, i. e., the plunger members 46, 47, 48 are parallel to the side bars 2, 3, and to these plunger members 46, 47, 48 are secured the afore- 20 said angles or lengthening members 51. Each plunger corresponds to a shelf or rather to the space above the shelf, the lower plunger moving over the machine bed 33. The plunger body member or plate 60 25 is provided near the centre of the surface opposite to that on which the plunger members 52 are carried, with ears 61 carrying a pin 62 to which is journaled the jaw 63 at the upper end of the plunger arm 64, the 30 said arm being pivoted at its lower extremity 65 to the rear end of rearwardly extending arm 65' of a depending bracket 66 formed on the yoke. This bracket also carries the axis 67' of a bell crank lever 67, the 35 horizontal arm of which carries at its extremity a treadle 68, the upright arm 69 of this lever being connected by a rod 70 with an intermediate point 711 on the plunger arm 64. A spring 71 secured at one end 40 to the horizontal arm 67 and at the other end to the frame of the machine tends to raise the treadle and withdraw the plunger, the reverse action being accomplished by the downward pressure of the foot on the 45 treadle.

In the operation of filling the cases or boxes with cans or packages, the articles forming each group are separated from the supply and loaded into the case at the corresponding stroke of the plunger or plungers; that is, each stroke is a complete operation of cutting off loading and feeding for the next stroke. The cutting off of the load is accomplished by means of the separators already referred to in connection with the description of the combined adjustments. More particularly, the separating mechanism consists of an upright separator shaft 59 carrying the separator arms 38, 39, 40 50 extending transversely of the shaft and adjustable along the shaft, that is, in a direction transverse to the feed. One of these arms corresponds to each tier of cans or packages. Each arm in the form of the invention shown is mounted on a hub or boss

75 adapted to slide along the shaft for purposes of adjustment and held in position by a set screw 76. Secured to the lower end of the shaft is the toothed gear 77 of the intermittent type having at the point where the teeth are omitted a surface 78 curved inward toward the center on an arc to fit the corresponding convex curve 79 on an idler 80. The teeth of this idler mesh with the teeth of the gear 77 and with the teeth of a 75 segment 81 which swings on a stud 82 actuated by a pin 83 carried on the plunger carriage and co-operating with a cam slot 85 in the segment.

The gears are so arranged that as the 80 plunger moves forward the action of the pin 83 on the cam slot 85, swinging the segment 81 to the left, rotates the gear 80 to the right or clockwise and the gear 77 to the left or counter-clockwise until the convex portion 85 79 on the gear 80 engages the concave portion 78 on the gear 77, locking the parts against rotation. In this position of the parts, the separator arms 38, 39, 40 intersect the path of the cans and preferably engage 90 the first can of the supply on each tier, thus separating the supply back of the separator from the load in front of the plunger. In this connection it should be noted that while the separator arms are thus moved into the 95 path of the cans and preferably brought into contact with certain cans in the supply which it is desired to cut off from the group in front of the plunger, they are merely brought in contact and not thrust against 100 these members so as to force the supply backward along the track or conveyor.

It will be apparent that on the withdrawal of the plunger and plunger carriage, the pin 83, again cooperating with the cam 105 slot 85, will return the mechanism to the position illustrated in Figure 1. The locking effect produced by the engagement of the convex portion 79 with the concave portion 78, being such that while it resists any tendency to rotation imparted to the gear 77, as by pressure of the cans on the arms 38, 39, 40, it is easily released by rotation of the gear 80 swinging the convex portion 79 out of contact with the concave portion 78 carried by the gear 77. The motion of the segment is also limited by the stationary pin 58 in the arcuate slot 58' in the segment.

Co-operating with the separators and with the plungers in this machine, we have the 120 can stops 35, 36, 37 already referred to. The function of these can stops is first to act as an abutment for positioning the cans in front of the plunger, that is, there is one can stop at the end of each shelf forming a stop 125 for each tier of cans and co-operating with each separator arm. On the withdrawal of the plungers, and prior to or on the withdrawal of the separator arms from the path of the can supply, the can stops are thrust 130

forward or more properly moved in a direction opposite to the feed, in which position they receive and arrest the foremost can advancing to fill the space in which the 5 cans are grouped in the path of the plunger from which the previous load has just been removed, having been thrust into the packing funnel. The can stops remain in the advanced position, receiving and holding the 10 cans as described until the plunger has been withdrawn and starts on its return stroke. Then after the separator arms are actuated and caused to engage the foremost cans of the supply for the purpose of cutting off the 15 group in front of the piston from the supply, the can stops are withdrawn a short distance to permit the cans of the group thus cut off to advance in the direction of the feed a distance sufficient to permit them to clear 20 the foremost cans of the supply so that there will be no scraping of labels or jamming of cans or packages by contact of the group being loaded with the cans being fed when the group is thrust forward by the plunger 25 or plungers.

This is accomplished by the following group of mechanism. The can stops 35, 36, 37 are mounted each on one of three horizontal arms 56, each secured by a set screw 30 to the upright shaft 57. This shaft which has its bearings in the end frame 16, has at its lower extremity or more properly just about the lower bearing an arm 93 projecting nearly at right angles to the arms 56. 35 This arm is given a tendency to swing forward in the direction of the stroke of the plunger by the spring 92 which acts upon the lower can stop lever tending to pull this lever and swing the other can stop levers 40 backward in the direction of the can feed. The swing of the lever 93 imparting the forward motion to the can stops, the motion bringing them up to the position in which they first receive the cans, i. e., the motion 45 contrary to the can feed, is produced during the withdrawal of the plunger, the plunger itself or more properly the lower righthand angle iron extension 51 coming in contact with the end of the lever 93. 50 This lever and hence the action of the can stops is further controlled by an automatic latch and escapement mechanism indicated in a general way by reference character 94 and illustrated in detail in Figures 5 and 6, 55 Figure 5 being a view looking at this mechanism from the right in Figure 3, and Figure 6 being a view looking at the same mechanism from the direction of the front of the machine. The function of this latch and escapement is to hold the can stops stationary in the advanced position in which they receive the cans. The period during which they are thus held corresponds to that in which the plunger is, or more properly the 60 plungers are in retracted position, which

coincides with the period during which the separators 38, 39, 40 are withdrawn, the pin 83 being at or near the rear end of the slot 85 of the separator mechanism. Figures 5 and 6 show fragmentarily the end of the 70 lower plunger in withdrawn position and in the relation which it occupies at this time to the latch mechanism.

This latch mechanism consists of a latch member 95 pivoted on the frame or on a 75 suitable bracket thereon at 95', and an escapement or pawl member 96 pivoted on the latch at 96', both swinging in a vertical plane parallel or substantially parallel to the motion of the plunger. This pawl or escapement 96 engages a stop pin 100 on the latch and is normally held in contact with the stop by a tension spring 97 which engages the latch and a stationary guide bracket 99 on the frame to be hereinafter described. The pawl 96 has a flat rear surface 96" which is vertical when the escapement or pawl is in normal position, i. e., resting against the pin 100, and an inclined face 96''' which is forwardly disposed. The 80 spring 97 controls not only the escapement pawl 96 but the latch 95 upon which the escapement is mounted, for in normal position the escapement is rigid with the latch and the spring imparts to the latch a tendency to counter-clockwise rotation as viewed in Figure 5. The angle iron extension 51 on the plunger engages the end of the can stop actuating lever 93, swinging it backward and bringing the can stops into forward position, 100 i. e., moving them in a direction opposite to the can feed. This lever is engaged by the vertical depending flange of the angle, as shown, particularly in Figure 6, at a point spaced inward from the end, and at the extreme end 98 of the angle, the vertical flange is removed, leaving the flat or horizontal end 98 to co-operate with the escapement and latch.

To return to the operation, the plunger 110 having been withdrawn, swinging the lever 93 to its extreme rearmost position and bringing the can stops forward to the point at which they receive the cans released by the separators, the latch 95, impelled by the 115 spring 97 which actuates both the escapement and the latch as already pointed out, swings downward in front of the lever 93, a notch 101 in the rearmost end of the latch receiving and engaging the top foremost corner of the corresponding section of this lever. This position of the parts, particularly the can stops, is predetermined but adjustable by moving frame 16 providing for the feeding in front of the plunger of a 120 load of cans which exactly fits between the rear stops in this position and the separators. Figures 5, 6 and 7 show these parts in corresponding positions, that is, the separators are withdrawn from the path of the 125 130

cans and the can stops are advanced and held in advanced position at the same period, i. e., at the rear end of the plunger stroke so that the load is positively measured. Immediately the plunger begins to advance on the forward or loading stroke, the separators are actuated as will be observed by examination of Figure 7, the rear end 85' of the cam slot 85 being the separator actuating portion and the front end the locking portion of the stroke. The action of the can stops is almost simultaneous with that of the separators; in other words, as the plunger moves forward, the end 98 of the plunger extension engages the rear 96" of the escapement pawl 96, swinging the latch 95 clockwise about its center 95', releasing the lever 93 so that the spring 92, acting on the lower can stop arm, draws the can stops 35, 36, 37 slightly to the rear, providing the clearance referred to. The bracket 99 with its inclined forward surface 102 projecting forward toward the center of the machine, acts as a guide for the plunger to prevent the end 98 of the angle 51 from being forced upward by the resistance of the latch. The function of the escapement proper is exercised on the return stroke of the plunger. At this time the rear end of the latch 95 is resting on top of the lever 93. As the flat end 98 of the angle 51 encounters the escapement 96, it engages the inclined surface 96"" thereof and the spring 97 yields, permitting the escapement to swing in counter-clockwise direction about its pivot 96', so that the parts return to their locked position without injury. As the plunger reaches the end of its rearward traverse, it brings the lever 93 again to the position illustrated in Figures 5 and 6, and the latch 95, impelled by the spring 97, swings in front of the lever which is again engaged by the notch 101 at the rear end of the latch.

The object of thus manipulating the can stops is to first measure the load by a pre-determined spacing between the separators, and the advanced position of the can stops, and the purpose of moving them backward is to cause them to clear the foremost cans of the supply without any necessity for pushing the supply backwards which has resulted in cramping and hence cutting off the supply, and in crushing of the containers. By thus providing a clearance, rubbing of the containers and damaging of the labels and other injury which would otherwise result, is prevent.

Having further reference to the details of the machine, it will be noted that instead of the old style chute by means of which the cans are led to the case, I have in the present instance provided a funnel 104 tapered near its mouth at 104'. This makes it possible to pack the cans much more closely which is regarded as important to

the use of paper boxes which are being largely substituted for the old-fashioned wooden cases. To operate effectively for the purpose described, this funnel must be of thin material, and to give it the necessary rigidity, is corrugated at 104", the corrugations being parallel to the filling stroke and intervening between the lines of cans. Also in the line of further adjustability, the funnels are made in different sizes to conform to the different sized cases, and are made detachable, being secured by bolts 105 in brackets 106 beneath the funnel 104. The cases or boxes while being filled, are supported on suitable supports or brackets 107 provided with rollers 108 and beneath the funnel with rollers 109 supported on springs 110, so that the cases are held against the funnel with a yielding pressure.

Another detail of importance in connection with the adjustability of the machine relates to the provision of bridges 112. This subject-matter is best shown in Figure 4 on the front or reverse side of the machine from that illustrated in Figure 3. These bridges, preferably in the form of angle plates as shown extending in the direction of feed at each side, are of different lengths and interchangeable by reason of a number of holes 113 receiving thumb screws 114. These bridges are made short for the large diameter cans to prevent bridging or closing of the space through which the cans are fed into the lower tiers and long to prevent double feeding of the small cans. The angles are placed on each side of the feed space to correspond to the tracks.

Another feature of the invention relates to the connection of the run-down by which the cans are fed to the tracks. The run-down or chute 115 carries a spring plate 116 at the side which overlaps the side plate of the machine and prevents contact of the can with the forward edge of the side plate.

The operation of the machine is similar in a general way to that of the machines described in applicant's prior patents already cited in this case. The cans, empty or filled, or packages to be loaded into the cases or boxes, are fed to the run-down or chute 115 by any suitable means as a conveyor or the like. From the run-down or chute 115 the cans pass between the sides 4 and 5 on to the lower distributing track 117 leading to the bottom track 25. When the bottom track and the bottom distributing channel are filled, the cans pass this first channel 117 to the second distributing channel 118 leading to the middle or intermediate one of the tracks 25. When the middle tracks 25 of the channel 118 are filled, the cans pass to the top track 25. To assist the distribution of the cans, bridges 112 between the channels 117 and 118 are provided. With small cans long bridges are used to

prevent double feeding, and with the large cans short bridges are used to prevent bridging of the channel or wedging of the cans in the channel with consequent closing of the channel when it is not filled.

An important feature of the machine is the universal adjustability both as to length of cans, diameter of cans and number and size of the cans in the load. This is accomplished by lateral adjustment of the front side plate 4 by means of the slot 9 and bolt 8, and by changing the length or point of engagement of connecting studs or struts 10, 10' and 10'', and the lateral adjustment of the front upright 11 by virtue of corresponding slot 14 and bolt 14'. These adjustments are for the purpose of changing the width of the tracks. The vertical spacing of the tracks is changed by the slot 20 and screw adjustment 26, 27 shown in Figure 3, the same being determined by the arcuate slots in the swinging plates 28 on both sides of the machine, see also Figure 4. As the shelves 31, 32 which support the load as distinguished from the supply, rest at one end on the corresponding tracks, the one adjustment at this point serves for both the tracks and the shelves. The other ends of the shelves are supported on cross bars 30 42, 43 in the end frame 16, see Figure 2, and are made adjustable by means of the series of holes 44 to be engaged by bolts 45. The variation of length of the load is provided for by adjustment lengthwise of the machine, i. e., in the direction of the feed of the cans of the end frame 16, see Figure 2, the same being adjusted along the side bars 23 by loosening bolts 18. The separators 38, 39, 40 are also adjustable along 40 their shaft 59 to provide for variation of the size of the cans, etc. The can stops may be adjusted by moving the can stop arms 56 up and down the shaft 57, and the length of the plungers may be changed by moving 45 the extension members 51, changing the position of the bolts 53 in the holes 54. In fact, the construction of the machine is made so completely flexible as to provide for every variation of the size of the packages, 50 the number to be packed and the size of the cases, it having already been pointed out that the funnel is removable and interchangeable for other size funnels.

In practice the channels 117, 118 which 55 are usually made of sufficient depth not to require adjustment, are filled with the cans or packages which are fed continuously, keeping the tracks 25 likewise full according to the sequence of operations in the present 60 machine. When the plunger is in its extreme rear position, the can separators 38, 39, 40 are withdrawn from the path of the cans, but this period of withdrawal is short as will be obvious from examination of the 65 separator mechanism Figure 7, particularly

the cam slot. At the same time, the can stops are locked in forward position by the escapement mechanism already described, the forward position being the farthest advanced position which these stops assume in the direction from which the cans are fed. The cans or packages move forward and fill the space in front of the plunger, the can stops thus measuring the load which is cut off by the separators immediately the plungers start the forward or loading stroke. The separators 38, 39, 40 are swung into the path of the cans and locked and in immediate sequence before the plungers come in contact with the cans the separators are permitted to withdraw a short distance, sufficient to permit the cans which are being loaded into the case by this particular stroke of the plunger to clear the forward cans of the supply and prevent 80 damage, as already pointed out, obviating the necessity for causing the separators to thrust the cans of the supply backward to provide this clearance with the danger of crushing the cans and of cramping them 90 and thus interrupting the feed.

Having thus described my invention, what I claim and desire to secure by Letters Patent is:

1. In a machine for filling cases with cans or packages, having a loading means, means for reciprocating the same and a feed intersecting the path of the loading means, means for grouping the cans in the path of the loading means, including a support, a can stop at the end of the support which is remote in the direction of feed, a separator at the opposite end of the support, means for moving the separator into the path of the cans prior to their engagement by said loading means and withdrawing the separator to permit feeding of the next group, means for moving the can stop in a direction opposed to the feed and withdrawing it after the separator has entered the path of the cans.

2. In a machine for filling cases with cans and similar packages, having a reciprocating plunger and a feed for leading cans into the path of the plunger, means for grouping the cans for engagement by the plunger consisting of a support, a separator near one end of the support and means for moving the same into and out of the path of the can feed, a can stop adjacent the other end of the support, and means for moving the same in a direction opposed to the feed while the plunger is withdrawn, and withdrawing it prior to the thrust of the plunger.

3. In a machine for filling cases with cans and similar packages, having a reciprocating plunger and a feed for leading cans into the path of the plunger, means for grouping the cans for engagement by the plunger consisting of a support, a separator near one

end of the support, and means for moving the same into and out of the path of the can feed, a can stop adjacent the other end of the support, means for advancing the can stop in a direction opposed to the feed to receive the cans and determine the number to be cut off by the separator and withdrawing it after the separator has moved into the path of the cans and prior to the engagement of the cans by the plunger.

4. In a machine for filling cases with cans or packages, a plunger, means for actuating the plunger, means for feeding the cans into the path of the plunger, an oscillating separator and means for moving the separator into the path of the feed prior to the engagement of the cans by the plunger, and withdrawing the separator to permit feeding of the next group, the stroke of the separator being only sufficient to stop the cans without thrusting them backward in the direction from which they come.

5. In a machine for filling cases with cans or packages, having a loading plunger, means for reciprocating the same and a feed intersecting the path of the plunger, means for grouping the cans in the path of the plunger, including a support for the cans, a can stop at the end of the support which is remote in the direction of feed, an oscillating separator at the opposite end of the support, means for moving the separator into the path of the cans prior to their engagement by the plunger and withdrawing the separator to permit feeding of the next group, the forward motion of the separator being sufficient to stop the cans without imparting any backward motion to them, a stop in the path of the cans and beyond the plunger and means timed to operate after the action of the separator providing for the movement of the stop in the direction of the feed.

6. In a machine for loading cases with cans or packages, having a plunger, means for supporting the cans in the path of the plunger and means for feeding them thereto, a separator for cutting off the load from the supply, the same including a finger, and means for swinging the finger into a position in the path of the cans and substantially at right angles to the feed.

7. In a machine for loading cases with cans or packages, including a plunger, means for supporting the cans in the path of the plunger and means feeding them thereto, a separator for cutting off the load from the supply, the same including a finger, and means for swinging the finger into a position in the path of the cans and substantially at right angles to the feed prior to the engagement of the cans by the plunger, and swinging it backward in the direction of the feed to permit feeding of the succeeding load as the plunger is withdrawn.

8. In a machine for loading cases with cans or packages, having a plunger, means for supporting the cans in the path of the plunger and means for feeding them thereto, a separator for cutting off the load from the supply, the same including a finger and means actuating the finger, swinging it into a position in the path of the cans and substantially at right angles to the feed and swinging it backward in the direction of the feed, the said means for actuating the finger including a lock for holding the finger rigidly in stopping or separating position in the path of the cans and releasing it.

9. In a machine for loading cases with cans or packages having a plunger, means for supporting the cans in the path of the plunger and means for feeding them thereto, a separator for cutting off the load from the supply, the same including a finger and means for swinging the finger into a position in the path of the cans, said means including intermittently meshing, toothed gears having co-operating locking means.

10. In a machine for loading cases with cans or packages, having a plunger, means for supporting the cans in the path of the plunger, and means for feeding them thereto, a separator for cutting off the load from the supply, the same including a finger and means for swinging the finger into a position in the path of the cans, said means including toothed gearing and a segment with a cam slot and a pin carried by the plunger engaging said slot to actuate the separator.

11. In a machine for loading cases with cans or packages, having a plunger, means for supporting the cans in the path of the plunger and means for feeding them thereto, a separator for cutting off the load from the supply, the same including a finger and means for swinging the finger into a position in the path of the cans and substantially at right angles to the feed, said means including toothed gearing and a segment with a cam slot and a pin carried by the plunger engaging said slot to actuate the separator, the gearing having locking means to hold the separator finger rigidly in a position which it takes intersecting the feed.

12. In a machine for filling cases with cans or similar packages, a feed, means for grouping the cans as fed, and means for thrusting the cans thus fed and grouped into the case, the grouping means including a can stop and a separator, means for moving the can stop in a direction opposed to the feed and withdrawing it while the plunger is withdrawn, means for moving the separator into the path of the cans prior to the engagement of the group by the thrusting means and while the can stop is advanced, and withdrawing the separator to permit the cans to be fed and to engage the stop in the advanced position of the latter.

13. In a machine for filling cases with cans or similar packages having feeding means and a plunger moving transversely to the feed, a can stop for holding the cans in the path of the plunger and a separator co-operating therewith, means for actuating the can stop, advancing it contrary to the feed and retracting it, said means including a rotary shaft, an arm secured to the shaft substantially at right angles thereto and supporting the stop, an arm on the shaft actuated by the plunger on its withdrawal stroke to move the stop into advanced position, means for locking said arm to hold the can stop in advanced position, and means actuated by the plunger in its forward or thrusting stroke to release said lock. 65
14. In a machine for filling cases with cans or similar packages, having feeding means and a plunger moving transversely to the feed, a can stop for holding the cans in the path of the plunger and a separator co-operating therewith, means for actuating the can stop, advancing it contrary to the feed and retracting it, said means including a rotary shaft, an arm secured to the shaft substantially at right angles thereto and actuating the stop, an arm on the shaft actuated by the plunger on its withdrawal stroke to move the stop into advanced position, means for locking the stop in said position, and means actuated by the plunger to release said lock. 70
15. In a machine for filling cases with cans or similar packages, having feeding means and a plunger moving transversely to the feed, a can stop for holding the cans in the path of the plunger and a separator co-operating therewith, means for actuating the can stop, advancing it contrary to the feed and retracting it, said means including a rotary shaft, an arm secured to the shaft substantially at right angles thereto and actuating the stop, an arm on the shaft actuated by the plunger on its withdrawal stroke to move the stop into advanced position, means for locking the stop in advanced position, and means actuated by the plunger in its forward or thrusting stroke to release said lock. 75
16. In a machine for filling cases with cans or similar packages, having feeding means and a plunger moving transversely to the feed, a can stop for holding the cans in the path of the plunger and a separator co-operating therewith, means for actuating the can stop, advancing it contrary to the feed and retracting it, said means including a rotary shaft, an arm secured to the shaft substantially at right angles thereto and actuating the stop, an arm on the shaft actuated by the plunger on its withdrawal stroke to move the stop into advanced position, means for locking said arm to hold the can stop in advanced position, and means actuated by the plunger in its forward or thrusting stroke to release said lock. 80
17. In a case filling machine having a feed, a plunger and a separator, a can stop, means actuated by the plunger to move the can stop in a direction opposed to the feed to receive the cans, means for holding the stop in advanced position and means actuated by the plunger on its return or forward stroke for releasing the can stop permitting the load to move slightly in the direction of feed, separating it from the supply. 85
18. In a case filling machine having a feed, a plunger and a separator, a can stop, means actuated by the plunger to advance the can stop in a direction opposed to the feed to receive the cans as released by the separator, said means consisting of a pivoted lever extending into the path of the plunger and actuating the can stop, a latch for locking the said lever holding the stop in advanced position, and an escapement carried by said latch to be engaged by the plunger on its forward stroke as the load is cut off by the separator to trip the latch and release the can stop, permitting the load to advance in the direction of feed, separating it from the supply by a space sufficient to prevent the contact of the supply with the load during the loading stroke. 90
19. In a machine for filling cases with cans or similar packages, a feed, a reciprocating plunger, a separator and a stop, means for advancing the stop in a direction opposed to the feed as the plunger is withdrawn, means for locking the stop in advanced position, means for releasing the stop on the return stroke of the plunger, the same consisting of an escapement pawl controlling the locking means and engaged by the plunger. 95
20. In a machine for filling cases with cans or similar packages, a feed, a reciprocating plunger, a separator and a stop, means for advancing the stop in a direction opposed to the feed, means for locking the stop in advanced position, means for releasing the stop, the same consisting of an escapement controlling the locking means and engaged by the plunger, and a guide for the plunger in the vicinity of the escapement to prevent deflection of the plunger in said operation. 100
21. In a machine for filling cases with cans or similar packages, feeding means consisting of a plurality of inclined tracks spaced apart in a substantially vertical direction, a plunger reciprocating on a path transverse to the feed, the plunger carrying a plurality of plunger members elongated in the direction of feed and spaced apart to correspond to the spacing of the tracks, 105

- supporting means for the cans in continuation of each track, means for adjusting the tracks as to their width, means for adjusting the tracks and supports as to their vertical spacing, and means for adjusting the plunger members as to their length.
22. In a machine for filling cases with cans or packages, a plunger having vertically spaced engaging members holding the cans, a feed consisting of a plurality of sets of inclined tracks spaced apart in a substantially vertical direction, means for adjusting the tracks to change their transverse spacing, a plurality of supports in the path of the plunger engaging members continuous with the tracks, and means for adjusting the tracks and supports in a vertical direction to correspond to the adjustment of the tracks.
23. In a machine for filling cases with cans or packages, feeding means, a plunger reciprocating transversely to the feeding means, a plurality of supports for holding the packages in the path of the plunger, the same being spaced apart in a vertical direction, the plunger having a plurality of can or package engaging members likewise spaced, said members being adjustable as to their length.
24. In a machine for filling cases with cans or packages, a feed consisting of a plurality of sets of inclined tracks spaced apart in a substantially vertical direction, means for adjusting the tracks to change their transverse spacing, reciprocating loading means consisting of a plurality of plungers spaced in an upright direction, a plurality of supports beneath the path of the reciprocating means continuous with the tracks, means for adjusting the supports and tracks to change their vertical spacing, a separator having separator fingers corresponding to each support and each engaging member on the plunger, and means for adjusting said fingers in a vertical direction.
25. In a machine for filling cases with cans or packages, feeding means, a plunger reciprocating transversely to the feeding means, a plurality of supports for holding the packages in the path of the plunger, the same being spaced apart in a vertical direction, the plunger having a plurality of can or package engaging members vertically spaced, said members being adjustable as to their length, i. e., in the direction of the feed, separating means and a can stop at the end of each support, and means for adjusting the normal position of the can stops in the direction of the feed.
26. In a machine for filling cases with cans or packages, a feed, a plunger, reciprocating on a path intersecting the feed, supports for holding the cans or packages in the path of the plunger, the same being spaced transversely to the feed, the plunger having a plurality of can engaging members elongated in the direction of the feed and spaced transversely to the feed to correspond to the spacing of the supports, separator fingers corresponding to the supports, spaced in a direction transverse to the feed and adjustable in the direction of spacing, can stops corresponding to the supports and likewise vertically adjustable.
27. In a machine for filling cases with cans or packages, a feed, a plunger, reciprocating on a path intersecting the feed, supports for holding the can or packages in the path of the plunger, the same being vertically spaced, the plunger having a plurality of can engaging members elongated in the direction of the feed and vertically spaced to correspond to the spacing of the supports, separator fingers corresponding to the supports vertically spaced and adjustable in the direction of spacing, can stops corresponding to the supports and likewise vertically adjustable, the engaging members on the plunger being elongated in the direction of the feed and adjustable as to their length, and means for adjusting the can stops in the direction of the feed.
28. In a machine for filling cases with cans or similar packages, a reciprocating plunger, means for feeding cans to the plunger consisting of sharply inclined channels, means for adjusting the apparatus to accommodate different sized cans consisting of bridging means removably attached at the mouth of the channels and adapted to be replaced by other bridging means of different lengths to determine the size of the opening and prevent double feeding of small cans and bridging of the opening by the larger cans.
29. In a machine for filling cases with cans or packages, a plurality of tracks, upright supports for the same, and means for adjusting the tracks vertically consisting of a slot and screw connection and a swinging plate for each such slot and screw connection, the same being slotted transversely to the aforesaid slot to determine the points of adjustment.
30. In a machine for filling cases with cans or packages, a reciprocating plunger having a plurality of engaging members, means for feeding cans or packages to the plunger and supporting the cans or packages in the path of the plunger consisting of a plurality of sets of tracks spaced apart in a substantially vertical direction and a plurality of supports likewise spaced and arranged in continuation of the tracks, means for adjusting the tracks vertically, each support resting at one end on the tracks to be adjusted therewith, and means for adjusting the other end of the supports.

31. In a machine for filling cases with cans or packages, a reciprocating plunger having a plurality of engaging members spaced apart in a substantially vertical direction, supports for holding the cans or packages in the path of each of said engaging members, a can stop adjacent the end of each support and an upright frame carrying the can stops, means for adjusting the frame in the direction of the length of the supports to change the adjustment of the stops. 65
32. In a machine for filling cases with cans or packages, a reciprocating plunger having a plurality of engaging members spaced apart in a substantially vertical direction, supports for holding the cans or packages in the path of each said engaging member, a can stop adjacent the end of each support and an upright frame carrying the can stops, means for adjusting the frame in the direction of the length of the supports to change the adjustment of the stops, and means for adjusting the length of the engaging members. 70
33. In a machine for filling cases with cans or packages, a filling plunger having a plurality of can engaging members spaced in a substantially vertical direction and elongated transversely to the spacing, feeding means including a plurality of vertically spaced tracks and sharply inclined channels, means for adjusting the width of the channels and tracks, a plurality of supports for holding the cans or packages in the path of the can engaging members, bridging means removably attached near the mouths of the channels and adapted for replacement by others of different lengths for determining the capacity of the channels, means for adjusting the tracks and supports in the direction of their spacing, means for adjusting the length of the can engaging members carried by the plungers, can stops and means for adjusting the position of the can stops in the direction of the length of the tracks and supports. 85
34. In a machine for filling cases with cans or packages, a filling plunger having a plurality of can engaging members spaced in a substantially vertical direction, feeding means including a plurality of vertically spaced tracks and sharply inclined channels, means for adjusting the width of the channels and tracks, a plurality of supports for holding the cans or packages in the path of the can engaging members, bridging means removably attached in the mouths of the channels and adapted for replacement by others of different lengths for determining the capacity of the channels, means for adjusting the tracks and supports in the direction of their spacing, means for adjusting the length of the can engaging members carried by the plungers in the direction of the feed, separators spaced in a vertical direction, means for adjusting them in the direction of the spacing, can stops at the ends of the supports, means for adjusting the can stops in the direction of the length of the supports and tracks, and means for adjusting them vertically. 90
35. In a case filling machine, a feed, a plunger and a separator, can stops, means for moving the can stops in a direction opposed to the feed to receive the cans, means for moving the can stops forward to support the load, an upright adjustable frame carrying said stops, and means for adjusting the frame back and forth in the direction of the feed. 95
36. In a machine for filling cases with cans or similar packages, feeding means, a plunger moving on a path intersecting the feed, means for grouping the cans in the path of the plunger, means for guiding the groups of cans or packages into the cases in the form of a funnel, the grouping means being adjustable to provide for variations as to the number and diameter of the cans, and the funnel being removably attached and adapted for replacement by others of different sizes to co-operate with the adjustment of the grouping means. 100
37. In a machine for filling cases with cans or packages, a feed, a plunger moving on a path intersecting the feed, engaging means including supports for holding the cans or packages in the path of the plunger, the supports being vertically spaced and vertically adjustable to vary the sizes of the groups, a funnel in line with the plunger, the same being removably secured and adapted for replacement by others of different sizes to correspond to the variation of the sizes of the groups. 105
38. In a machine for filling cases with cans or packages, feeding means, a plunger moving on a path intersecting the feeding means and having a plurality of engaging members spaced apart in a vertical direction, means for adjusting the engaging members as to their length, supports for holding the cans or packages in the path of each said engaging member, a separator and a can stop adjacent the opposite ends of the supports, means for varying the distance between the can stops and separators, a funnel to receive and guide the cans as thrust forward by the plunger, the funnel being removably secured and adapted for replacement by others of different sizes to correspond to the said adjustments. 110
39. In a machine for filling cases with cans or packages, feeding means, a plunger moving on a path intersecting the feeding means and having a plurality of engaging members spaced apart in a vertical direction, supports for holding the cans or pack- 115
- 120
- 125

ages in the path of said plunger, cut-off means and a can stop adjacent the opposite ends of the supports, means for varying the distance between the can stops and separators, a funnel to receive and guide the cans as thrust forward by the plunger, the funnel being removably secured and adapted for replacement by others of different sizes to correspond to the said adjustments. Signed by me at Baltimore, Maryland, 10

5 this 27th day of February, 1919.
